UNITED STATES PATENT OFFICE.

JAMES BARZILLAI HOWARD, OF INDIANAPOLIS, INDIANA.

HEATING-STOVE.

SPECIFICATION forming part of Letters Patent No. 710,460, dated October 7, 1902.

Application filed January 4, 1902. Serial No. 88,448. (No model.)

To all whom it may concern:

Be it known that I, JAMES BARZILLAI HOWARD, a citizen of the United States, residing at Indianapolis, in the county of Marion and State of Indiana, have invented certain new and useful Improvements in Heating-Stoves; and I do hereby declare the following to be a full, clear, and exact description of the invention, such as will enable others skilled in the art to which it appertains to make and use the same.

The present invention is an improvement upon the construction of heating-stoves shown and described in Letters Patent of the United States issued to me June 13, 1899, bearing No. 629,997.

The object of the present invention is to provide a construction whereby the air can be more highly heated preparatory to its delivery to the combustion-chamber and the delivery of hot air to the combustion-chamber controlled. To accomplish this, I provide three air-chambers—first, a preliminary air-warming chamber around the ash-chamber; second, an air-heating chamber around the fire pot, the air-warming chamber communicating with the air-heating chamber through a contracted passage, and, third, a hot-air reservoir circumambient the top of the fire-pot, a ring-valve being provided between the air-heating chamber and the hot-air reservoir to regulate the supply of hot air to the reservoir, and consequently to the smoke and gases to be consumed rising from the fuel.

In the accompanying drawings, illustrating the improvements, Figure 1 is a central vertical section taken on a plane passing through the front and back of the stove, the top of the stove being omitted. Fig. 2 is a central vertical section taken on a plane at right angles to the plane on which Fig. 1 is taken and looking toward the front or air-supply side of the stove. Fig. 3 is a horizontal sectional view taken on a plane just above the grate. Fig. 4 is a similar view taken on a plane slightly above the air-outlets of the hot-air reservoir. Fig. 5 is an edge view of the hot-air reservoir, the valve-ring removed. Fig. 6 is a plan view of the same.

In the several views, 1 denotes the ash-chamber.

2 is the fire-pot, and 3 the grate for sustaining the fuel in the fire-pot.

The ash-chamber has an adjustable valve-damper 1^a, admitting air to support combustion of the fuel on the grate. Surrounding the ash-chamber on three sides is an air-warming chamber 4, having openings on opposite sides of the air-opening to the ash-chamber provided with adjustable valve-dampers 4^a. 55 Surrounding the fire-pot is an air-heating chamber 5, there being a narrow or contracted opening 5^a between the chambers 4 and 5. The air-heating chamber 5 extends entirely around the fire-pot. Above the air-heating 60 chamber 5 is an annular hot-air reservoir 6, bulging inward over the fire-pot and provided at its under side with a series of vents 6^a to direct the hot air into the smoke and gases rising from the fuel. 70

Between the air-heating chamber 5 and the hot-air reservoir 6 is a perforated annular shoulder or septum 7, on which slides an annular perforated ring-damper 7^a, having a handle, by which it can be moved, projecting 75 through a slot to the exterior of the stove, so that the flow of hot air from the air-heating chamber to the reservoir 6 can be nicely regulated.

The air-supply for the fuel on the grate is 80 entirely separate from and independent of the air-supply for the air warming and heating chambers and reservoir, the vertical walls 1^b and horizontal wall 1^c being provided for the purpose. 85

From the foregoing it will be observed that the supply of air to the under side of the fuel can be regulated to suit the rapidity of combustion desired, and the supply of hot air injected into the smoke and gases can be regulated to suit the quantity to be consumed; but to effectively do this the two supplies must be regulated to each other. Because of the comparatively narrow channel of communication between the air-warming chamber 4 and the air-heating chamber 5 large volumes of insufficiently-warmed air cannot be admitted to the chamber 5, and consequently a supply of uniformly-heated air in the reservoir 6 is insured. In other words, 90 the progress of air through the air-heating chambers is retarded, so as to insure thor- 95

ough heating of the air in the chamber 5. The hot air flowing from the reservoir 6 can be regulated by the ring-damper to accord exactly with that required to effect a consumption of the smoke and gases. This matter of insuring a high temperature of the air injected into the smoke and gases is important, because such smoke and gases can only be consumed by the intermingling intimately therewith air in sufficient quantity at a high temperature.

With this invention the many evils of the smoke nuisance are eliminated or mitigated without expensive appliances.

15 What I claim, and desire to secure by Letters Patent, is—

1. In a heating-stove having an ash-pit and a fire-pot, a chamber for warming air around the back and sides of the ash-pit and isolated 20 from said ash-pit, a valved opening thereto, a chamber surrounding the fire-pot for heating air, a contracted opening connecting the said two chambers, a hot-air chamber or res-

ervoir around the top of the fire-pot and discharging thereinto, a contracted opening connecting the aforesaid air-heating chamber and the last-named chamber or reservoir and a damper arranged to control said contracted opening, substantially as described. 25

2. In a heating-stove having an ash-pit and 30 a fire-pot, a chamber for warming the air around the back and sides of the ash-pit and isolated from said ash-pit, a valved opening thereto, a chamber surrounding the fire-pot for heating air, a contracted opening connecting the two said chambers, a hot-air reservoir around the top of the fire-pot and discharging thereinto, a contracted opening connecting the aforesaid air-heating chamber and the reservoir, substantially as described. 35 40

In testimony whereof I affix my signature in presence of two witnesses.

JAMES BARZILLAI HOWARD.
